CONVERTIBLE CONTAINER AND DISPLAY STAND

Rolf A. Samsing, Braintree, Mass., assignor to The Gillette Company, Boston, Mass., a corporation of Delaware
Filed Sept. 24, 1964, Ser. No. 398,894
7 Claims. (Cl. 206—44)

ABSTRACT OF THE DISCLOSURE

A display stand comprising a blank folded to form a foot member and an upright back member, the latter having an undulating slit therein for receiving and retaining an upright mast portion of a metal rod which also includes a laterally extending foot section.

This invention comprises a new and improved container convertible into a stand for hang-up cards displaying small articles of merchandise, such as safety razor blades or the like.

An object of the invention is to provide a reliable container in which a set or number of display cards may be conveniently packed for storage, safely shipped without damage through any channels of commerce to agents or retail merchants, and then set up on counters or in show windows and converted into stands for displaying their contents on hang-up display cards.

To this end the container of my invention includes in its structure panels of sheet material so folded as to provide a cover, a two-ply base and an upright back member. The back member has an undulatory or sinuous slot therein leading toward the base. With these panels of sheet material is combined a metal rod or bracket having a mast portion interlocked with the back member through the medium of its said slot, an angular foot engaged between the plies of the base and an overhead hanger from which the display cards may be suspended.

The container may be loaded or filled at the factory with a selected number of display cards and closed by folding the cover panel. This results in a substantially square package that may be conveniently stacked in storage or wrapped for further handling.

Upon receipt the retail dealer has only to lift the cover panel into upright position where it is locked by foldable wings that extend across the fold line of the cover panel.

The cooperative arrangement of the slotted back panel and the angular metal bracket constitutes a feature of the invention that contributes to the ease and facility of assembling the elements of the container and to its sturdy and reliable structure in respect to both of its functions. This feature may be usefully incorporated in display stands of sheet material whether or not they have the additional function of a container.

These and other features of the invention will be best understood and appreciated from the following description of a preferred embodiment thereof, selected for purposes of illustration and shown in the accompanying drawings, in which:

FIG. 1 is a plan view of the blank,

FIG. 2 is a fragmentary rear view of a portion of the stand,

FIG. 3 is a view of the metal bracket,

FIG. 4 is a front view in perspective of the stand in empty condition,

FIG. 5 is a rear view in perspective of the stand with a full load of display cards, and

FIG. 6 is a view in perspective showing the cover panel folded in the closed position of the container.

The convertible container and display stand in its pre-

2

ferred embodiment may be constructed from a single blank of cardboard or other stiff and resilient sheet material. Such a blank is shown in FIG. 1 as comprising a rectangular back panel 10 merging into substantially square foot panels, 11 and 12, defined by transverse scored fold lines. At its upper edge as shown in FIG. 1 the back panel 10 merges into rectangular cover panels 13 and 14 also defined by scored lines.

The back panel 10 is provided with a long vertical slit 15 of sinuous or undulatory conformation that provides intercalated tongues herein shown as being of rounded contour though these may be of angular contour if desired. The slit 15 terminates at its upper end in a recess formed by a downwardly extending tongue 16 and at its lower end in a recess formed by an upwardly extending tongue 17. These tongues 16 and 17 are resilient and tend always to spring back into the plane of the panel 10 from which they are cut. The back panel has also a wide shallow recess in its lower edge formed by a flange 18 that projects from the inner foot panel 11.

The outer foot panel 12 has in its outer edge a pair of spaced tongues 19, which, when the panel is folded, project into the recess of the back panel above the flange 18 and so lock the foot panels in their folded and superposed relation as shown in FIG. 5.

The inner cover panel 13 is provided with side flanges 20 defined by scored fold lines. The outer cover panel 14 merges into shallow back flaps 21 also set off by scored fold lines. These fold lines are intersected by a pair of inwardly extending elongated wings 22 cut out from the material of the panel 14 by diagonal cuts as best shown in FIGS. 1 and 2, and defined by longitudinal scored fold lines, interrupted by cuts forming locking tabs 22' that extend from the wings into the flaps. The outer cover panel 14 is folded rearwardly against panel 13 and glued or otherwise fastened thereto but leaving the wings 22 unattached. When the laminated cover panels 13 and 14 are folded in forming a container or package the wings 22 remain in the panels and are folded with them as shown in FIG. 6.

When serving as a display stand the cover panel 13 is erected as shown in FIGS. 4 and 5. The wings 22 upon being folded outwardly are locked in position substantially at right angles to the laminated cover panels by the locking tabs 22' which bear against the rear face of the cover panel 13 to retain the latter in its upright position where it serves as a flag carrying advertising or price information.

The parts made of sheet material have now been summarized and the metal rod or bracket 34 with which they are assembled will now be described. This bracket as shown in FIG. 3 has an upright mast portion 30 which merges into an overhead forwardly extending hanger portion 31 and merges downwardly into right angled foot portion 32 angularly displaced with respect to the hanger portion. The foot portion 32 in turn merges into an arm 33 transverse with respect to the hanger portion 31. The mast portion 30 is somewhat longer than the distance between the recesses formed by the tongues 16 and 17. The bracket is continuous throughout its length and may be formed of spring tempered steel wire 0.105" in diameter or thereabout.

In assembling the stand for loading the panel 10 is bent at right angles with respect to the panel 11 and the mast portion 30 is forced rearwardly through the undulating vertical slit 15 and locked in place behind the tongues of the slit by the tongues 16 and 17 with the foot portions 32 resting on the panel 11 as best shown in FIG. 4. The panel 12 is now folded over the panel 11 and the foot portion 32 and the spaced tongues 19 are forced through the opening provided by the cut out flange 18. The

bracket is thus securely locked to the panel 10 and is held against twisting by the transverse arm 33 disposed between the laminated panels 10 and 11 adjacent to the fold vertex with the hanger arm 31 projecting at right angles to the back of the stand.

As herein shown a series or collection of display cards 28 may be suspended in parallel relation from the hanger arm 31. These cards may carry small articles of merchandise such as a package 29 of razor blades shown in FIG. 6. It will be seen that the suspension and arrangement of the cards 28 are not disturbed either by folding the cover panels into closed position as seen in FIG. 6 or by erecting them into the display position as shown in FIG. 5.

Having thus disclosed my invention and described in detail an illustrative embodiment thereof, I claim as new and desire to secure by Letters Patent:

1. A convertible container and display stand comprising an integral blank folded to present a two-ply laminated base and an upstanding back panel, the back panel having an undulating vertical slit terminating at its upper end in a recess, in combination with a metal rod having an upright intermediate mast portion located behind said vertical slit, a right angular foot engaged between the plies of said base, and an overhead arm extending forwardly through the said recess of the back panel.

2. A convertible container and display stand comprising panels so folded as to provide a cover, a two-ply base and an upright back member, the latter having an undulatory slit therein leading toward the base, in combination with a metal rod having a mast portion interlocked with the back member at its said slit, an angular foot engaged between the plies of the base and an overhead hanger projecting from the back panel member.

3. A convertible container and display stand as described in claim 2, further characterized in that the two-ply base is formed with a fold vertex at one edge and the

metal rod has a laterally extending foot section enclosed in said fold vertex.

5. A display stand comprising panels of resilient sheet material including a foot member and an upright back member having an undulating slit leading toward the foot member with a recess-forming tongue at the upper end of the slit, in combination with a metal rod having a straight mast portion adapted to be forced through the slit of the back member to displace the said tongue and become interlocked with the material of the back member and a laterally extending foot section.

metal rod has a laterally extending foot section enclosed in said fold vertex.

5. A display stand comprising panels of resilient sheet material including a foot member and an upright back member having an undulating slit leading toward the foot member with a recess-forming tongue at the upper end of the slit, in combination with a metal rod having a straight mast portion adapted to be forced through the slit of the back member to displace the said tongue and become interlocked with the material of the back member and a laterally extending foot section.
